Primary Examiner — Jack Reickel*Assistant Examiner* — Michael A Kervin(74) *Attorney, Agent, or Firm* — Egbert, McDaniel & Swartz, PLLC(57) **CLAIM**

The ornamental design for a tool holder, as shown and described.

DESCRIPTION

FIG. 1 is an upper perspective view of a tool holder showing my new design;

FIG. 2 is a front view thereof;

FIG. 3 is a rear view thereof;

FIG. 4 is a side view thereof;

FIG. 5 is an opposite side view thereof;

FIG. 6 is a top plan view thereof;

FIG. 7 is a bottom plan view thereof;

FIG. 8 is a first lower perspective view thereof; and,

FIG. 9 is a second lower perspective view thereof.

The circular shapes illustrated in broken lines in FIGS. 1, 2 and 6 depict unclaimed portions of the tool holder that form no part of the claimed design.
